UNITED STATES PATENT OFFICE.

JOHN S. JOBE, OF MONACA, PENNSYLVANIA, ASSIGNOR TO UNITED STATES SANITARY MANUFACTURING COMPANY, OF MONACA, PENNSYLVANIA.

ENAMELING-KILN.

SPECIFICATION forming part of Letters Patent No. 774,478, dated November 8, 1904.

Application filed August 19, 1904. Serial No. 221,400. (No model.)

To all whom it may concern:

Be it known that I, JOHN S. JOBE, a citizen of the United States, residing at Monaca, in the county of Beaver and State of Pennsylvania, have invented or discovered certain new and useful Improvements in Enameling-Kilns, of which improvements the following is a specification.

The invention described herein relates to certain improvements in the construction of kilns for burning enamel-ware, the invention being especially applicable to kilns for bathtubs, &c., and has for its object a construction whereby one of the kilns may be maintained at a higher heat than the other.

The invention is hereinafter more fully described and claimed.

In the accompanying drawings, forming a part of this specification, Figure 1 is a sectional plan view, the plane of section being indicated by the line I I, Fig. 2. Fig. 2 is a vertical section on a plane indicated by the line II II, Fig. 1. Fig. 3 is a similar view on a plane indicated by the line III III, Fig. 1, looking in the direction of the arrow *a*; and Fig. 4 is a view similar to Fig. 2, illustrating a modification of my improvement.

In the practice of the invention it is preferred that the chambers A and B should be formed in the same structure and covered by a common arch 1, the chambers being separated by vertical walls extending from the floor of the furnace to the crown of the arch, as shown in Figs. 2 and 4. These series of flues or passages 2, 3, and 4 are formed under the floor of these chambers. One set of flues, 2, extend from one side of the furnace—as, for example, the left-hand side or end in Figs. 1 and 2—under chambers A and B to uptake-flues 5 in the outer wall of the chamber B, the uptake-flues communicating with the chamber, preferably by perforations 7. The flues 3, preferably double the number of flues 2, extend from the opposite or right-hand end of the furnace under the chambers B and A to the uptake-flue 5^a in the outer wall of the chamber A, said uptake-flues communicating with the chamber A by perforations 7^a. The flues 4 extend from one end of

the furnace under the chamber A and communicate with the uptake-flue 6 in the inner wall of said chamber and connected thereto near its upper end. Into the outer end of each of the flues 2, 3, and 4 are inserted burners 9, which are connected to a supply-pipe 10. Combustion occurs at or near the entrance end of these flues, the air for such combustion being supplied through the air-ports 11. It will be seen from the foregoing that the bottom of the chamber A will be subjected to the heat from a large number of the flues and that the side walls formed by the inner walls of the uptakes 5^a and 6 are heated, respectively, by the products of combustion from a large number of the passages or combustion-chambers. Hence this chamber will be more highly heated than the chamber B, which is employed as a drying-chamber, and is heated by the products of combustion from three of the combustion chambers or passages 11 along its outside wall and by the radiated heat from nine passages under its floor. The products of combustion escape from these chambers through ports 12 into the down-take-flues 13, which communicate at the lower 75 ends with the horizontal flue 14 and a vertical uptake 15 connected to the stack.

In the construction shown in Fig. 4 the floor-flues 2, 3, and 4 are arranged as in Fig. 1 and connecting, respectively, with the uptakes 5, 5^a, and 6^a, the latter forming the separation-wall between the chambers. This uptake-flue 6^a communicates at its upper end directly with the stack, and ports 16 are formed through its walls for the escape of 85 products of combustion into the uptake and thence to the stack. In this construction, as in that shown in Figs. 1 to 3, the chamber A will be much more highly heated than the chamber B, the latter being employed as the 90 heating-chamber and the former as a burning or finishing chamber for the enamel. The charging-openings into these chambers are closed by double doors, and provision is made for simultaneously swinging the doors of each 95 chamber. To this end the doors are secured to vertical shafts 17, provided at their lower ends with beveled pinions 18, adapted to in-

termesh with pinions 19 on a rotating shaft or sleeve. In order that both sets of doors may be operated from one end of the furnace, the pinions 19 for the chamber A are mounted on 5 a sleeve 20, supported in suitable bearings in the front of the furnace. The shaft 21 passes through the sleeve 20 and has the pinions 19 for the doors on chamber B secured thereto. It will be understood from the foregoing that 10 by operating either one of the handles 22 or 23 either set of doors may be opened at will.

I claim herein as my invention—

1. An enameling-kiln having in combination 15 two chambers, two series of flues or combustion-passages passing from the ends of the kiln and connected to the chambers at the opposite ends, one of the series consisting of a larger number than the other series, an uptake between the chambers and a series of flues 20 or combustion-passages extending under one chamber and connected to the central uptake, substantially as set forth.

2. An enameling-kiln having in combination 25 two chambers, each having uptake-flues along

their end walls, two series of combustion flues 25 or passages extending from the ends of the kilns to the uptakes at the opposite ends of the kiln, an uptake between the chambers and a series of flues or passages extending under one chamber and connected to the central uptake, 30 substantially as set forth.

3. An enameling-kiln having in combination 35 two chambers, each having uptake-flues along their end walls, two series of combustion flues or passages extending from the ends of the kiln to the uptakes at the opposite ends of the kiln, an uptake between the chambers and connected thereto and to the stack and a series of flues or passages extending under one chamber and connected to the central uptake, 40 substantially as set forth.

In testimony whereof I have hereunto set my hand.

JOHN S. JOBE.
